CLAIM

(57) The ornamental design for the agricultural planter, as shown and described.

DESCRIPTION

FIG. 1 is a perspective view of the agricultural planter showing our new design, the portion in phantom lines in the figures forming no part of the claimed invention;

FIG. 2 is a top view thereof;

FIG. 3 is a bottom view thereof;

FIG. 4 is front view thereof;

FIG. 5 is a rear view thereof;

FIG. 6 is a side view thereof; and,

FIG. 7 is an opposite side view thereof.
